UNITED STATES PATENT OFFICE.

JAMES M. ENGLAND, OF DALLAS, TEXAS.

STORE DISPLAY ROOM.

Application filed June 26, 1922. Serial No. 570,837.

To all whom it may concern:

Be it known that I, JAMES M. ENGLAND, a citizen of the United States, residing at Dallas, in the county of Dallas and State of Texas, have invented certain new and useful Improvements in Store Display Rooms, of which the following is a specification.

This invention relates to new and useful improvements in store display rooms.

10 In the displaying of electric lighting fixtures to customers it is customary to hang the same from the ceiling in close relation and to place wall-lights in scattered or miscellaneous order on the walls of the store room. The best display given the customer is the lighting of fixtures one after the other and if two are lighted at the same time very little opportunity is given for comparison, owing to the presence of daylight and other 20 lights in the store room. As these fixtures are generally displayed in an open show room the customer is unable to judge the appearance of the fixture under night conditions.

25 The object of my invention is to provide a lighting fixture display room free from daylight or other lights when closed and to arrange in the same individual booths or compartments in each of which, a fixture 30 may be individually displayed under night time conditions.

A further object is to provide means for concealing all ceiling fixtures except the one being displayed or those being compared.

35 A further object is to provide means for display-wall lighting fixtures in substantially a natural position and in such relation to the ceiling fixtures as to give a realistic display and afford an opportunity for 40 satisfactory comparison.

A still further object is to provide individual switches for the ceiling fixtures and closures for the booths to be opened when the switches are operated.

45 A construction designed to carry out the invention will be hereinafter described together with other features of the invention.

The invention will be more readily understood from a reading of the following 50 specification and by reference to the accompanying drawings, in which an example of the invention is shown and wherein:

Fig. 1 is a perspective view of a portion of a display room constructed in accordance 55 with my invention,

Fig. 2 is a plan view of the room, the fixtures being indicated diagrammatically,

Fig. 3 is a detail showing the inner side of the curtains of a booth,

Fig. 4 is an enlarged cross-sectional detail, and

Fig. 5 is a detail of one of the ceiling switches.

In the drawings the numeral 10 designates a room which may be of any suitable 65 shape and which is preferably without windows as the latter would have to be covered to exclude daylight. I have shown a rectangular room as this will more frequently be the shape employed. A door 11 is provided for entering the room and the same may have a floor covering. It is customary to use an ornate carpet completely covering the floor and to furnish the room with high grade furniture so as to more nearly simulate the furnishings of the living rooms of 75 the better class of homes.

Built against the walls 10 of the room are booths 12, three walls being utilized in the drawings. The booths are formed by partition walls 13 projecting outwardly from the walls 10 of the room and extending from the floor to the ceiling. At the front edge of each wall 13 is placed a casing mullion 14 and two of these mullions case the sides 85 of a booth. At the corners of the room a dead space 15 is formed and the mullions 14 of the adjacent booths intersect at right angles. A cap molding 16 extending along the ceiling at the top of the mullions gives 90 a finish to the booths.

The partition walls 13 as well as the exposed portions of the walls 10 of the room within each booth may be plastered or otherwise finished. A composition building 95 board has been used satisfactorily. These walls may be papered, painted or otherwise ornamented and may also be paneled in contrasting colors. Each booth may have a different interior color scheme.

While various closures for each booth might be employed, I have found hanging curtains to be more pleasing and harmonious. In the entrance to each booth I mount a tubular curtain pole 17 across the 105 top. This pole has a longitudinal slot 18 in its bottom as is indicated in Fig. 4. Rings 19 have heads 20 sliding in the pole, the shanks passing thru the slot. A pair of hanging curtains 21 of any suitable mate- 110

rial are attached to the rings. A single cord 22 is formed into an elongated loop which is passed thru the rings.

At one end the loop passes over a pulley 23, while at the other end the free ends of the cord pass thru a double pulley 24. The ends of the cord hang from the pulley 24 and are preferably of uneven length so as to be more readily selected. A knob 25 may be placed on one end of the cord and a knob 26 on the other end. The front length of the cord loop is secured to the ring at the inner or central end of one of the curtains, while the other curtain has its inner ring attached 15 to the rear length of the cord loop. From this it will be seen that when one of the cord ends is pulled the front and rear lengths of the cord move in opposite directions and the curtains attached thereto are likewise moved. 20 Thus by grasping the knob 25 and pulling the same the cord is moved so that the curtains 21 are slid apart and the booth opened. By pulling on the knob 26 the curtains are closed. When a knob is pulled the other is 25 elevated, therefore the knob to be operated is always uppermost. It is to be understood that other ways of having and operating the curtains or other closures, may be used.

30 In each booth is mounted an electric lighting ceiling fixture or chandelier A, a different fixture being hung from the ceiling in each booth. Main circuit wires B and C extend along the booths and branch wires 35 D lead from the wire B to each fixture A. From each fixture A a wire E leads to a pull switch 27 mounted on the ceiling in the front left corner of the booth. A cord 28 having a button 28' on its lower end hangs 40 down on the opposite side of the booth from the knobs 25 and 26. By pulling in the cord 28 the switch is operated.

On each mullion 14 a bracket or wall lighting fixture G may be mounted at the usual 45 height of such fixtures. Each fixture G is connected with the wire B by a branch wire H and with the wire C by a branch wire J. All wires of course are concealed and the fixtures are mounted in an attractive 50 manner. The wall fixtures G have their own switches and may be individually lighted. The wall fixtures may be omitted and only ceiling fixtures displayed if desired.

In using the display room the booth curtains 21 are normally closed and the room is 55 dark. The salesman enters the room in advance and illuminates the same either by lighting one of the wall fixtures G or by lighting a ceiling fixture in the center of the 60 room, which is not shown. After the customers are seated the salesman extinguishes all lights and standing before one of the booths he grasps the knob 25 in his right hand and the button 28' in his left hand, he pulls both,

whereby the curtains 21 are slid back and 65 the ceiling fixture A in the booth is lighted at the same time. The customer sees this fixture substantially as it will look when installed and observes it to the best advantage, not being bothered with conflicting or clash- 70 ing lights.

If it should be desired to select a wall fixture to harmonize with the ceiling fixture, one of the fixtures G may be lighted and a 75 realistic demonstration given. The fixtures A in the different booths may be exhibited and if the customer desires to make a comparison between two fixtures, these may be left lighted or they may be alternately lighted. By keeping the curtains of all 80 booths closed except those of the booth in which the ceiling fixture is being exhibited, the attention of the customer is not detracted and the sale is much more quickly and easily made. It is obvious that wall paper or 85 draperies may be hung up in the booth to obtain a comparative effect with fixture. Instead of the pull switches 27 other styles of switches could be used and the invention is not to be limited to such. 90

Various changes in the arrangement and location as well as modifications may be made without departing from the spirit of the invention and within the scope of the appended claims. 95

What I claim, is:

1. In an electric light fixture display room, a room from which the daylight is excluded when closed, a plurality of display booths built against the walls of the room and facing inwardly of the room, each of said booths being decorated and furnished according to different color schemes, display fixtures arranged in said booths to be lighted selectively, and curtains adapted to shut the interior of the booths from view, whereby the booths may be separately viewed from the room, or more than one quickly alternately viewed for comparison. 100

2. In an electric light fixture display room, a room from which daylight is excluded when closed, a pair of sets of display booths arranged within the room, said sets being arranged angularly with relation to each other, said booths facing inwardly of the room, each of said booths being decorated and furnished according to different color schemes, display fixtures arranged in said booths to be lighted selectively, and means adapted to shut the interior of each booth from view, the angular arrangement of the sets of booths permitting each booth to be conveniently separately viewed from a central position within the room, or more than one booth quickly alternately viewed from such central position for comparison. 110

In testimony whereof I affix my signature.
JAMES M. ENGLAND.
